No. 707,130.

Patented Aug. 19, 1902.

W. T. LUCIE.

STOPPING DEVICE FOR LOOMS.

(Application filed Apr. 21, 1902.)

(No Model.)

UNITED STATES PATENT OFFICE.

WILLIAM T. LUCIE, OF EASTON, PENNSYLVANIA.

STOPPING DEVICE FOR LOOMS.

SPECIFICATION forming part of Letters Patent No. 707,130, dated August 19, 1902.

Application filed April 21, 1902. Serial No. 103,842. (No model.)

To all whom it may concern:

Be it known that I, WILLIAM T. LUCIE, a citizen of the United States, residing in Easton, in the county of Northampton and State of Pennsylvania, have invented certain new and useful Improvements in Stopping Devices for Looms; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates to looms, and particularly to narrow-ware looms; and it has for its object to provide an improved construction of mechanism for stopping the operation of a loom whenever a stoppage or ill-timed 20 movement occurs in the action of the rack-bar with reference to the action of other parts of the loom.

The invention consists in an improved stop mechanism for looms constructed substantially as will be hereinafter described and finally embodied in the clauses of the claim.

25 In the accompanying drawings, Figure 1 is a top plan view of my invention, showing enough of the loom to properly illustrate the 30 invention; and Fig. 2 is a side view of what is seen in Fig. 1.

In said drawings, *a* is a portion of one side frame of the loom; *b*, the breast-beam; *c*, the batten carried by lay-swords *d*; *e*, the reciprocating rack-bar, and *f* one of the shuttle-blocks.

35 On the side frame *a* is secured, as by bolts *g*, a substantially L-shaped arm *h*, carrying a pair of slotted brackets *i*, which support 40 and in whose slots *j* is guided, by means of pins *k*, a block *l*. The pins *k* are carried by and project downwardly from the block *l*, their guiding action being augmented by bolts *m*, which are carried by the arm *h* and 45 penetrate the block *l* in such manner that said block is free to slide thereon. The block *l* carries a push-rod or throw-off pin *n*, which projects toward and into an opening *o* in the arm *h*.

50 *p* is an adjustable arm made in two parts, having a slot-and-pin connection *q* between

them, whereby the adjustment of said arm is effected. This arm is carried by the rack-bar *e* and has its front end hook-shaped, as at *r*. By virtue of the combined actions of 55 the rack-bar and batten this arm normally takes an arc-shaped movement, which causes its hook-shaped portion *r* to pass out and around the block *l* without engaging it. Should the rack-bar stop moving, however, 60 or should its motion become ill-timed with reference to the action of the batten, said hook *r* will be caused to pull on said block *l*, and thus thrust the push-rod inwardly.

s is a plug which fits in the opening *o*. By 65 means of a chain *t*, passing around pulleys *u*, suitably arranged in stationary parts of the loom, this plug is connected with a rod *v*, which is adapted to impinge against a lug *w* on the hand-rail *x* of the loom, to which the 70 belt-shipper *y* is connected in the usual manner. When the plug *s* is in its opening *o*, it acts through the chain *t* to hold rod *v* out of engagement with the lug *w*, acting against a spiral spring *z*, which is coiled between one 75 end of a casing *l* and a shoulder *2* on said rod, said casing being secured to the breast-beam and receiving the coiled spring and serving as a support for the rod.

It being remarked that plug *s* is normally 80 disposed in the opening *o*, thus holding rod *v* out of contact with lug *w*, and that the inward thrust of the rod *n* will be sufficient to displace the plug from the opening, so as to release rod *v*, it is believed that in view of 85 the above-described coaction between parts *p* and *l* upon any irregularity in the action of the rack the operation of the mechanism will be fully understood.

Having thus fully described my invention, 90 what I claim as new, and desire to secure by Letters Patent, is—

1. In a stop-motion mechanism for narrow-ware looms, the combination, with the batten, of a reciprocating part on the batten mov- 95 able transversely of the movement thereof, a spring-pressed part adapted to actuate the power-controlling mechanism of the loom, a stationary part having an opening, a plug adapted to be received by said opening, op- 100 erative connecting means between the plug and said spring-pressed part, and means, con-

trolled by said reciprocating part, for forcing said plug from the opening, substantially as described.

2. In a stop-motion mechanism for narrow-
5 ware looms, the combination, with the batten,
of a reciprocating part on the batten mov-
able transversely of the movement thereof, a
spring-pressed part adapted to actuate the
power-controlling mechanism of the loom, a
10 stationary part having an opening, a plug
adapted to be received by said opening, op-
erative connecting means between the plug

and said spring-pressed part, and means, com-
prising coactive members carried the one by
said reciprocating part and the other by said 15
arm, for forcing said plug from the opening,
substantially as described.

In testimony that I claim the foregoing I
have hereunto set my hand this 7th day of
April, 1902.

WILLIAM T. LUCIE.
